UNITED STATES PATENT OFFICE.

EUGENE B. ANDES, OF LANCASTER, PENNSYLVANIA.

FIREARM.

1,415,976.

Specification of Letters Patent. Patented May 16, 1922.

Application filed March 6, 1922. Serial No. 541,348.

To all whom it may concern:

Be it known that I, EUGENE B. ANDES, residing at Lancaster, in the county of Lancaster and State of Pennsylvania, and citizen of the United States, have invented certain new and useful Improvements in Firearms, of which the following is a specification.

The object of this invention is to provide 10 an improved form of firearm, specifically, in the embodiment disclosed herein, a toy pistol, of the type adapted to use therein caps on a ribbon or tape that is fed, automatically, upon movement of the trigger, to present the caps successively to proper position 15 with relation to the hammer and anvil.

The invention is more particularly concerned with the provision of improved feeding means for the ribbon or tape, and contains 20 novel trigger-controlled mechanism, including a toothed or "star" wheel feeding-member engaging the tape.

The invention will be more fully understood by reference to the accompanying 25 drawings, in connection with the detailed description thereof hereinafter appearing. Like reference characters denote corresponding parts throughout the several views of the drawing. Briefly described:

30 Figure 1 is a view in side elevation of the pistol of my invention;

Figure 2 is a view in elevation, looking at the inner face of one of the two casing-shells of the pistol, showing the actuating mechanism carried thereby, the two connecting screws for the two shell sections and the pin upon which the tape or ribbon is wound being in section;

35 Figure 3 is a view similar to Fig. 2, but showing the position of the moving parts when the trigger has been pressed fully inward;

40 Figure 4 is a detached detail view, in side elevation, of the hammer;

45 Figure 5 is a detached detail view, in side elevation, of the toothed or "star" wheel; and

50 Figure 6 is a detached, detail view, in end elevation, of the hammer and toothed feed-wheel in co-operative position.

Referring, now, in detail, to the drawing:

1 and 2 designate the two, substantially similar shells or frame-sections of the pistol, retained in assembled position by suitable 55 securing means, such as bolts 3, 3.

4 designates the anvil integral with the

frame-section 2 and shaped as an elongated flat plate disposed in a plane at right-angles to the general plane of the section 2, and presenting a flat contact surface to the impact face of the head 5 of the hammer 6.

The hammer 6 is an elongated member, provided, toward the end thereof opposite the head 5, with an opening 6', whereby it may be suspended upon a pivot-pin 7 carried by the shell-section 2. The hammer is also provided, at the end thereof opposite the head 5, with two toes 8 and 9 and, therebetween, with a recess 10; and, on one face and at one marginal edge, with a lug 6^a having an inclined top face and a vertical or straight end face.

The trigger 11 is suspended from the pin 12, and swinging movement of the trigger is limited, in one direction, by the top part 13 thereof impinging against one end of the flange 14 of the section 2. The trigger carries, at one longitudinal side and toward the bottom thereof, a pin 15, on which the sear is provided.

The sear is, roughly, in the form of a bell-crank lever, having the longer arm 16 and the shorter arm 17. The longer arm, at its free extremity, is recessed, as shown at 18, in which recess the toe 9 of the hammer 6 rests, normally, as shown in Fig. 2. The shorter arm 17 is provided with a stop pin 17', which is adapted to ride into contact with the adjacent marginal edge of the hammer 11, thus limiting movement of the sear, independent 90 of the trigger, in one direction.

A toothed or "star" wheel feeding-member 19 is provided with a central opening 20, through which the pivot pin 7 projects, as shown in Fig. 2. The toothed wheel 19 is disposed against the hammer 6, face to face, and is provided, on the face thereof adjacent the hammer 6, with a plurality of equidistantly spaced lugs 21, formed similarly to the lug 6^a.

Normally, the straight or vertical face or wall of the lug 6^a of the hammer 6 bears against the corresponding vertical wall or face of one of the lugs 21 of the toothed wheel 19, whereby, as the hammer 6 is rocked back away from the anvil 4, said lug 6^a will (by reason of such engagement of the lug with the corresponding lug 21) swing said "star" wheel through the arc of a circle, thereby feeding the tape 23 bearing at intervals explosive fulminate caps 24.

Each two adjacent fulminate caps on the

tape are preferably spaced a sufficient distance so that, in the feed of the tape by the "star" wheel 19, the teeth 22 of the latter will engage the tape between such caps, as shown in Fig. 2. There is, thus, a specific combination between the tape and the "star" wheel.

The tape 23 is wound upon a pin 25 carried by the shell-section 2, and passes up between the anvil 4 and the hammer-head 5, as shown in Fig. 2.

A resiliently-supported, tape-guiding member 26 is formed as an elongated plate having an offset upper portion 27, the free end 15 thereof bearing against the adjacent or rear face of the anvil 4. The guide-member 26 depends below and above the anvil 4, as shown in Fig. 2. A spring 29, disposed between the offset portion 27 and a lateral 20 flange 30 of the shell-section 2, tends to press the guide-member 26 toward the "star" or toothed wheel 19.

A spring is coiled around the pin 7, as shown at 31, and one arm 32 of such spring 25 bears against a projection 33 on the head 5 of the hammer 6, while the other arm 34 bears against the pin 12.

A second spring is coiled around the pin 12, as shown at 35, and one arm 36 thereof 30 bears against the flange 37 of the shell-section 2, while the other arm 38 bears against the shorter arm 17 of the sear and, thereby, functions to swing the longer arm 16 of the sear upward.

35 In operation, the trigger 11 is pressed inward, moving the sear 16—17 in the same direction, thereby, by reason of the engagement of the sear arm 16 with the lower end of the hammer 6, swinging the head 5 of the 40 latter away from the anvil 4, against the influence of the spring-arm 32. In the continued movement of the trigger and, with it, the sear, the tooth 8 of the hammer rides into contact with the upper surface or edge 45 of the arm 16 of the sear, forcing said sear-arm downward, or kicking the same out of engagement with the hammer 6. The hammer, now released, is now, by the spring arm 32, forcibly swung against the anvil 4, 50 to explode the cap on the tape 24 which is in the path of movement of the hammer-head 5.

During the movement, aforesaid, of the hammer 6 away from the anvil 4, the hammer, by reason of the engagement of the vertical wall of the tooth 6^a thereof with the corresponding vertical wall of the corresponding tooth 21 of the feed-wheel 19, rotates the feed-wheel through the arc of a 60 circle, thus feeding the tape 23 upward and presenting a fulminate cap thereon in proper position with relation to the anvil 4 and the hammer-head 5.

During the forward movement of the 65 hammer 6, toward the anvil 4, under the in-

fluence of the spring arm 32, as described, the feed-wheel 19 does not partake of such movement, because the projection 6^a of the hammer, by reason of the inclined face 6^b, rides or trails idly over the corresponding 70 inclined faces of the lugs 21 of the feed-wheel 19. The coil 31 of the spring 32—34 is disposed between the upper face of the wheel 19 and the inner face of the shell-section 1. Therefore, as the inclined face 75 of the lug 6^a rides up on the inclined faces of the lugs 21 of the hammer 6, the star-wheel 19 moves slightly away from the hammer 6 and the said coil 31 is compressed 80 slightly; but, as the hammer-head 5 strikes the anvil 4 and the movement of the anvil is arrested, said coil 31 expands to force the star-wheel 19 against the hammer 6, thereby bringing the straight or vertical wall 6^c of the lug 6^a into contact with the 85 corresponding straight wall of the adjacent lug 21 of the feed-wheel 19.

Simultaneously with the swinging forward of the hammer 6 in the direction of the anvil 4, the spring-arm 38 swings the sear-arm 16 upward into engagement with the hammer toe 9, and the trigger 11 is, at the same time, moved forward to its initial position.

Having thus fully described my invention, what I claim as new and desire to secure by Letters-Patent is:

1. In a pistol, an anvil, a hammer having an impact-head, a pin upon which said hammer is pivoted, a fulminate-cap tape adapted to move lengthwise between said anvil and the hammer impact-head, a trigger, means, actuated by the manual movement of said trigger and including a toothed wheel rotatably mounted on said pin and 100 engaging said tape, for feeding said tape between said anvil and hammer impact-head, and co-operating means carried by said hammer and wheel for coupling said wheel to said hammer for simultaneous 105 movement when the hammer is swung away from the anvil, and for permitting said wheel to remain stationary during the movement of the hammer toward the anvil.

2. In a pistol, an anvil, a pivoted hammer having an impact-head, a fulminate-cap tape adapted to move lengthwise between said anvil and said impact-head, a trigger, a sear carried by said trigger and releasably engaging said hammer, and a toothed, 120 tape-engaging and feeding wheel actuated by the hammer upon movement of the latter away from the anvil.

3. In a pistol, an anvil, a pivoted hammer having an impact-head, a fulminate-cap tape adapted to move lengthwise between said anvil and said impact-head, a trigger, a sear carried by said trigger and releasably engaging said hammer, a toothed tape-engaging and feeding wheel actuated 125 130

by the hammer upon movement of the latter away from the anvil, and spring means for moving said hammer toward the anvil.

4. In a pistol, an anvil, a pivoted hammer having an impact-head, a fulminate-cap tape adapted to move lengthwise between said anvil and said impact-head, a trigger, a sear pivotally carried by said trigger and releasably engaging said ham-

mer, spring means for normally maintaining said sear in releasable engagement with said hammer, and a toothed tape-engaging and feeding wheel actuated by the hammer upon movement of the latter away from the anvil.

In testimony whereof I hereunto affix my signature.

EUGENE B. ANDES.
